CLAIM

The ornamental design for a table top used for folding plastic composite flooring as shown and described.

DESCRIPTION

FIG. 1 is a front perspective view of the table top used for folding plastic composite flooring of the present invention; FIG. 2 is a left perspective view thereof; FIG. 3 is a front right perspective view thereof; FIG. 4 is left rear perspective view thereof; FIG. 5 is a top view thereof; FIG. 6 is a front view thereof; FIG. 7 is a back view thereof; FIG. 8 is a left side view thereof, the right side (not shown) forming a mirror image thereof; FIG. 9 is a bottom view thereof; and, FIG. 10 is a front plane environmental view thereof. The broken lines represent environmental subject matter and form no part of the claimed design.
